INVENTOR,

Peter Geary,
By J. M. Geary, Attorney.

UNITED STATES PATENT OFFICE.

PETER GEARY, OF STERLING, OHIO.

FENCE-POST.

SPECIFICATION forming part of Letters Patent No. 391,363, dated October 16, 1888.

Application filed February 14, 1888. Serial No. 263,953. (No model.)

To all whom it may concern:

Be it known that I, PETER GEARY, a citizen of the United States of America, residing at Sterling, in the county of Wayne and State of Ohio, have invented certain new and useful 5 Improvements in Fence-Posts, of which the following is a specification, reference being had therein to the accompanying drawings.

This invention pertains to certain new and useful improvements in fence-posts, having for its object the production of a new and improved form of posts embodying advantages in points of simplicity, durability, general efficiency, and expensiveness.

15 The invention consists, briefly, in the formation of a hollow post made of clay, said post having grooves formed therein for securing, by means of a suitable locking-plate, the fence-panels, and to this locking-plate can 20 also be secured wire strands when the same is employed in connection with a wire fence, and when so employed all slack in the wire is readily removed by means of said locking-plate.

25 The invention comprises the peculiar construction, combination, and arrangement of parts, substantially as hereinafter fully set forth, and particularly pointed out in the claim.

30 In the accompanying drawings, Figure 1 is a front elevation of my invention. Fig. 2 is an enlarged plan view thereof. Fig. 3 is a horizontal cross-section. Fig. 4 is a vertical longitudinal sectional view, and Fig. 5 is a detail view.

35 Referring to the drawings, A designates my improved fence-post, which I preferably make of clay, the same being burned and formed either square, round, or octagonal shape, according as may be desired. In the center of the body portion of this post is formed a vertical opening, *a*, of any desired shape, extending from end to end of the post, so as to reduce the weight thereof to a minimum. In practice the ends of this opening *a* are preferably fitted with blocks or plugs *a'* *a''*, so as to prevent water or dirt from lodging in said opening.

40 By this means a post is produced that is extremely light in weight and embodying a

great advantage in point of durability and 50 cheapness.

While the clay composing this post is in a green state I form in the front surface thereof by suitable means transverse grooves or recesses *b* *b*, wherein are disposed horizontal 55 fence-panels *B* *B*, as shown.

In the front surface of this post I form a longitudinal dovetail groove or recess, *b'*, extending, preferably, the entire length of said post; but, if desired, said groove or recess 60 need only extend to below the lowermost groove or recess, *b*.

C is a locking-plate having beveled sides and designed to fit within the dovetail groove or recess *b'*, the same being inserted after the 65 fence-panels have been placed in position, thereby firmly securing or locking said panels. By this means the panels are held without the need of any screws, nails, or wire, and if it is desired to remove any of the fence-panels—as, for instance, the lower ones to permit 70 of the passage of small animals—the same is readily effected by raising the locking-plate and removing the desired panels.

75 My invention is also applicable for use in connection with a wire fence, and when thus employed the wire strands D are secured to the outer surface of the locking-plate C by means of staples *d* *d*. When, as is always the case with wire fences, the wire slacks, such 80 slack can be readily removed or obviated by slightly raising the locking-plate, so as to draw tight said wire strands, said locking-plate being always firmly held in position by reason of its close fit in its dovetail groove or 85 recess.

From the foregoing description it will be seen that I have produced a fence-post extremely simple in construction, cheap, and durable, and that by means thereof a fence 90 can be readily and easily constructed, and parts removed, when desired, with but little trouble.

I do not confine myself to the use of the blocks *a'* for closing the longitudinal opening 95 in the post, as the same may be formed with closed ends of clay prior to being burned to prevent ingress of water.

I claim as my invention—
The herein-described improvement in fence-
posts, consisting of the hollow post of clay,
the blocks or plugs inserted in the ends thereof,
5 the front transverse grooves or recesses, the
longitudinal dovetail groove or recess, and
the locking-plate designed to fit in said dove-
tail groove or recess, and to be held thereby,
substantially as shown and described.

In testimony whereof I affix my signature in 10
presence of two witnesses.

PETER GEARY.
